UNITED STATES PATENT OFFICE

JAMES WAGNER, OF PENINSULA, OHIO

ARTIFICIAL-LIMB JOINT

Application filed June 7, 1928. Serial No. 283,548.

This invention relates to improvements in artificial limbs, and more particularly to the specific construction of the pivotal member or joint.

5 Among the objects in view is the provision of means for insuring the uniformity in the case of pivotal action of one limb member with respect to the other, and in greater detail, a further object is the avoidance of too 10 free pivotal action incident to looseness due to wear.

A still further object is the accurate adjustment and maintenance of just the desired freedom of or friction resistance to pivotal 15 movement.

With these and further objects in view, the invention comprises a joint for an artificial limb including a pivot bearing and means for taking up wear of the joint.

20 The invention comprises certain other novel constructions, combinations, and arrangements of parts, as will hereinafter in part become apparent and in part be stated.

In the accompanying drawings—

25 Figure 1 is a front elevation of knee joint workings of the artificial limb, incorporating an embodiment of the present invention.

Figure 2 is a view in side elevation of one of the pivot members, parts of the anchoring plates or straps being broken away for the saving of space.

Figure 3 is a view similar to Figure 2 with the castellated stud removed.

Figure 4 is a view similar to Figure 3, 35 with the top plate or strap removed.

Figure 5 is an enlarged detail perspective view of the castellated stud and its receiving nut.

Figure 6 is a transverse section taken approximately on the line 6—6 of Figure 2, parts being seen in elevation.

It is desirable to provide ease of pivotal movement of articulative sections of artificial limbs, but it is also desirable to avoid looseness at the place or places of the pivot or pivots. The present invention comprehends a combination of parts adapted for and capable of permitting perfect freedom for pivotal action while enabling the taking up of 50 wear if and when wear occurs. The inven-

tion is understood by reference to the accompanying drawing in which 1—1 indicates any two articulative parts or sections of an artificial limb, the pivotal connection or articulation being effected by the provision of 55 plates or straps 2—2 and 3—3 anchored in the respective sections 1, a plate 2 being pivoted at 4 to each plate 3. The pivotal connections 4 are duplicates of each other except for being rights and lefts as will be easily understood, and one is illustrated in detail in Figures 2 to 6 inclusive, from which it will be observed the strap or plate 2 terminates at its lower end in a bearing eye 5 shaped to cooperate with a bearing eye 6 at the upper end 60 of the strap 3. As seen best in Figure 6, the eye 6 is formed at the inner end with a bordering rabbet 7 adapted to receive the flange end 8 of a sleeve nut 9 which extends through the eye 6 and forms the bearing shaft. The sleeve 70 nut 9 extends beyond the eye 6 and through the bearing portion of the eye 5, the said bearing portion being formed with a flat part 10 snugly contacting with a flat area 11 on the sleeve nut 9 so that the said sleeve 75 nut moves angularly, that is, partially rotates, with the oscillations of the eye 5.

The eye 5 at its outer portion is preferably provided with a rabbet 12 to receive the castellated or star head 13 of a securing stud 80 or bolt 14^a, which stud or bolt is threaded into the sleeve 9 for securing the parts together. The eye 5 is also preferably provided with recesses 14—14, preferably adjacent the place of the flat section 10, and the web of 85 the eye inward of the rabbet 12 at the place of the recess 14 is provided with threaded apertures 15 for receiving a locking pin or bolt 16. The pin or bolt 16 is proportioned when threaded on one of the threaded apertures 15, 90 to have its head located in one of the radial recesses forming the castellations or star recesses of the head 13 so that when the pin 16 is in place, the bolt 14^a is incapable of movement independent of the eye 5, and since the 95 sleeve nut 9 moves with the eye 5, the parts 9, 14^a and 5 are locked by the screw 16 to a relatively fixed relation.

The eyes 5 and 6 may be interlocked to pivot together incident to presence of the 100

pivot formed by the sleeve 9 and bolt 14^a in any of several different ways, but by preference I have formed an outstanding boss 17 surrounding the aperture of eye 6, the said boss being in the form of a truncated cone, that is, tapering from the plane at which it springs from the plate forming the eye 6 out to its terminus. The plate forming the eye 6 surrounding the truncated cone 17 is also preferably slightly beveled as at 18 to form a circular inclined surface while the plate forming the nut eye 5 is provided with a similar but opposing inclined surface 19 corresponding and contacting with the surface 18, and the eye 5 being formed with a rabbet 20 at its inner face flaring and proportioned to snugly receive the truncated cone 17 as best seen in Figure 6.

Each of the plates forming respective eyes 5 and 6, is provided with stop shoulders 21-21, and 22-22 respectively located to limit the extent of possible pivotal swing of the plates or straps 2 or 3 with respect to each other to correspond with the extent of possible swing of the normal limb.

It will be observed that the conical contour of the boss 17 and inclined surfaces 18 and 19 insure availability of take up of wear because as wear occurs, the drawing of the plates nearer together by adjustment of the bolt 13 and consequent axial adjustment of sleeve nut 9, enables any desired degree of snugness of fit notwithstanding previous wear. Furthermore, the employment of the two threaded apertures 15 adjacent to each other, facilitates a nicety of adjustment of the bolt 13 for effective control of just the amount of friction between the two eyes 5 and 6 incident to the drawing of the sleeve flange 8 toward the head 13. If, when the nut 14^a has been adjusted so that one of the radial recesses of head 13 registers with one recess 14, the pivotal connection is too loose and only a slight forward adjustment of the bolt 14^a is required to give the desired friction, such forward adjustment will be accomplished by the placing of the bolt 16 in the next recess 14 rather than in the preceding one, or the conditions may be such that the bolt 16 has already been in the advanced recess 14 in which case the bolt 16 will be transferred to the rear recess 14 to register with the next advancing notch of head 13. The relative proportions of the webs between the notches of head 13 with regard to the spacing of the recesses 14, is such as to afford opportunity for fractional adjustment of the head 13 beyond that provided by the location of the several radial apertures of said head 13.

In other words, if only one aperture 14 were provided, it would be necessary to turn the head 13 through an angle large enough to bring one of the notches into alignment with the hole 14 to effect an adjustment. By providing two apertures which are spaced at a

different distance apart than are the notches in the head 13, it is possible to lock the bolt 14^a in successive positions which require rotation of less than one notch.

I claim:

1. A pivotal joint for artificial limbs of the class described, comprising, in combination, a pair of complementary plates formed with registering eyes, one of said plates having a truncated conical portion surrounding its eye while the other plate has a recess formed with a truncated conical side receiving the first mentioned conical portion on the other plate, a cylindrical sleeve extending through the eyes, a bolt engaging the sleeve and having a head formed with notches, and means for locking the headed bolt in an adjusted position consisting of a screw cooperating with one of the notches in the head and either one of a plurality of notches spaced apart on one of the plates a lesser distance than the notches that are spaced around the head whereby a nicety of adjustment is provided. 70

2. A joint for artificial limbs of the class described, comprising, in combination, a plate having an eye, a second plate having an eye in alignment with the first mentioned eye, a cylindrical sleeve having a flat portion and extending through said eyes, the second mentioned eye having the surface defining the said sleeve provided with a flat portion engaging with the flat portion of said sleeve, whereby relative rotation between these two parts is prevented, a castellated bolt threaded in the sleeve and provided with spaced notches around its periphery, the plate having a flat portion and being also formed with a plurality of notches spaced apart a lesser distance than the notches on the bolt, and a screw adapted to be threaded into either one of the notches on the plate in a position wherein it engages one of the notches on the bolt. 90

In testimony whereof I affix my signature.

JAMES WAGNER.
